THERMOSTATIC GENERATOR AND CONTROL DEVICE

Application filed October 20, 1928. Serial No. 313,747.

The present improvements relate, in general, to hydrocarbon stoves and more particularly to burners, vaporizers, and means for automatically controlling the fuel supply therefor and the functions thereof in general.

In devices of this character wherein hydrocarbon fluid is used as fuel, it is of paramount importance that features of safety are not overlooked in favor of features of utility. Due to the dangerous nature of the fuel employed, as well as the human element called upon to operate such apparatus, and for other reasons, it is essential that a fool-proof construction be devised. The present improvements therefore, have as their primary object, among others, the provision of a fool-proof apparatus of the type above mentioned, embodying features of safety and utility without sacrificing one in favor of the other. A further object is to provide a novel combination of elements whereby the fuel supply is automatically controlled. The provision of a thermally operated control means for the fuel supply both to the generator and burners comprises a further object of the improvements.

A still further object is to provide a novel arrangement of parts wherein the liquid fuel supply and vapor supply controls are synchronized so as to establish a ratio therebetween and between them and the burner or the vaporizer or each of them.

A novel combination of fuel burner and generator tube is also provided wherein the durability, efficiency and construction of the parts is greatly improved. Further objects and advantages will be apparent to those skilled in the art upon reference to the following description, and the accompanying drawings, in which—

Fig. 1 is a plan view of the preferred embodiment of the present improvements, portions in dotted lines, others in section, for convenience in illustration;

Fig. 2 is a side elevation of a burner and control means embodying the present improvements illustrated in Fig. 3;

Fig. 3 is a plan view similar to that illus-

trated in Fig. 1, but showing a modified construction.

Referring to the drawings, it is understood that the vapor burner 5 constitutes the main burner of a series of such burners commonly employed in a hydrocarbon stove (not shown). While the present improvements are illustrated and described in connection with such main burner, which serves not only as a service burner for cooking purposes but also as the heating medium for the vapor generator 10 wherein the vapor generated may supply side burners, it is evident that each burner itself may be equipped in the manner illustrated whereby but one generator supplies one burner.

Mounted on the stove in any convenient manner and adjacent burner 5, is a fixed member 6 provided with a passageway or conduit 7 therein. Said conduit communicates with a bore 8 in member 6, which bore is disposed at right angles to the conduit 7, although any other relation of parts may be employed. A pipe section 9 establishes communication between conduit 7 and the liquid fuel supply reservoir (not shown), and a suitable valve means (not shown) may be located between said conduit 7 and the reservoir to control the supply of liquid fuel, and the flame of the burners, or shut off said fuel.

The forward end of bore 8 is suitably threaded or otherwise adapted to fixedly support the tubular member 10, made of thermally responsive material, such as brass or other expansible and contractible metal. This tube 10 constitutes a vapor generator and is positioned so as to be disposed over the burner 5, in slightly spaced relation thereto so as to experience the thermal conditions thereof.

Secured to the outer end of generator 10 as for example by welding, is a bushing 11 having a bore 12 therein, a portion of said bore being formed to provide a conical valve seat 13 and another portion thereof provided with screw threads 16'. A vapor fuel supply conduit 14 is secured adjacent to said bushing 11, whereby communication from the generator 10 to the burner 5 is afforded, it being understood that a suitable mixing device for mix-

ing the vapor with air is interposed in this line, adjacent bushing 11 wherein the escaping vapor siphons air thereinto, as illustrated. As aforementioned, suitable connections may be made with pipe 14 to side burners if desired.

A valve stem 16 is disposed in bore 8 and chamber 15, one end of which terminates in a needle valve construction having a conical valve 17 adapted to seat on valve seat 13 and 10 completely shut off the vapor supply to the burner. Adjacent said valve 17, the stem 16 is externally screw threaded at 16", whereby said stem has a screw threaded connection with bushing 11 by the complementary 15 threads 16' thereon. This provision serves to support the valve stem as well as align the valve 17 with its seat 13, while at the same time, the stem 16 may be conveniently advanced or retracted by an operator turning 20 handle 18 for opening and closing valve 17 as well as moving the clean out needle to clean the orifice thereabout whenever desired or necessary. One or more longitudinally disposed channels 20 traverse the screw threaded 25 portion 16" for permitting passage of vapor from chamber 15 to bore 12.

As illustrated, a portion of said stem 16 extends through the bore 8 of the fixed member 6 and terminates therebeyond in a knob or operating handle 18. A bushing 19 surrounds stem 16 and closes the rear end of bore 8, suitable packing being provided in the bore 8 as well as elsewhere to form fluid tight connections, as illustrated. Said stem forms a 30 loose fit with the walls of bore 8 for permitting the passage of fluid from pipe 9, conduit 7 to chamber 15, communication between said last mentioned elements being afforded by the annular passageway 20' defined by the inner surface of bore 8 and the outer surface of stem 16.

As illustrated, a chamber 21 is bored in member 6 and communicates with conduit 7 at which point an auxiliary shut-off valve seat 45 21' is provided whereby to accommodate a fuel shut-off valve 22 for controlling passageway 7. Said valve 22 may form one end of a non-expansive rod 23, housed, suitably 50 packed and supported in chamber 21. The main portion of said rod, which may be of "invar" metal or the like, is disposed beside generator 10, slightly spaced therefrom and terminates in screw threads 24. The bushing 11 and rod 23 are operatively connected in fixed relation by means of brace 25, which is welded to the bushing and has a screw threaded nut 25' for receiving the screw threaded end of rod 23. The fixed relation of 55 these elements with generator 10 permits them to move as a unit. The screw threaded arrangement admits of adjustment between the parts, but it is obvious that the adjustable means may take other forms.

60 In the operation of the foregoing improve-

ments, any suitable priming means for initially heating the generator may be employed, e. g., a priming cup or an auxiliary lighter fed with fuel from the main or an auxiliary reservoir. Such auxiliary lighter 70 may be manually controlled or automatically controlled by suitable operative connections with the main burner control mechanism. When the apparatus is set up for use, the valve 22 is closed due to the fact that all the parts are cool and therefore the generator tube 10 is in its contracted state. Since said valve 22 controls the liquid fuel supply, the valve 17 may be disposed in any of several positions, since it is adapted to be manually operated 75 by stem 16 and handle 18. For example, the valve 17 may be closed against seat 13, or it may be opened at the time of lighting or left in any position when the stove is not in operation, since the valve 22, as aforementioned, 80 controls the fuel supply. Upon lighting the priming means, the generator tube 10 is heated up by means of the auxiliary flame, whereupon the generator tube 10 expands as it becomes heated, whereas the non-expanding 85 metal rod 23 does not expand. As the tube 10 lengthens in response to heat, the rod 23 moves therewith and the valve 22 is moved 90 away from seat 21', permitting the liquid fuel under pressure to flow from the supply 9 into the generator chamber 15. Since the tube and rod are fixed together, movement of one is experienced in like manner by the other.

It is readily apparent that the foregoing 95 operations do not transpire until the generator is sufficiently heated to vaporize the fuel which may go through into chamber 15. In the event that valve 17 is closed, it may now be manually opened by retracting stem 16 whereby the vaporized fuel may then proceed to the main burner, which is now lighted and the heat thereof continues to serve as the generating flame, in place of the auxiliary flame which may now be manually or automatically shut off. Where the valve 17 is 100 open at the beginning of the operation, the vaporized fuel, of course, proceeds therethrough to the burner, and in such case, said valve may be used manually for adjusting 105 purposes to afford a larger or smaller flame at the burner 5. The reverse action namely, contraction of the generator and closing of valve 22, takes place in case the auxiliary or main generating flame is inadvertently extinguished for any reason. Under such conditions of the burner, the generator tube 10 contracts as it cools and shortens, thus causing valve 22, actuated by the non-expanding rod 23, to close, thereby shutting off the 110 liquid fuel supply from pipe 9.

From the foregoing it is evident that the manually operated valve 17 controls the quantity of vapor proceeding from the generator to the burner. When it is desired to turn off the burner after use, the valve 17 may be 115 120 125 130 135

manually closed, shutting off the vapor and the flame, after which the valve 22 closes thermostatically as the generator 10 cools and contracts.

5 Referring to the modified form depicted in Figs. 2 and 3, it is notable that the valve stem 16 is provided with exterior threads at 30, thereby having screw threaded engagement with a similarly threaded portion of 70 bore 8. One or more channels 31, similar to channel 20 of the preferred form, is also provided for establishing communication between conduit 7 and chamber 15. The forward end of stem 16 is suitably supported in 75 the elongated sleeve 32 of bushing 11^a in which it loosely fits, thereby permitting passage of vapor therearound. In this form the stem may comprise a metal rod having a different coefficient of expansion than tube 10, if desired. By manually operating handle 18, it is apparent that the valve 17 in this embodiment may serve the same purpose and functions as it does in the preferred form.

25 A slightly different operation, however, is attained by this modified construction. When the apparatus is set up for use, the valves 17 and 22 are closed due to the fact that all the parts are cool and therefore the generator tube 10 is in its contracted state. Upon lighting the priming means, the generator tube 10 is heated up by means of the auxiliary flame, whereupon the generator tube 10 expands as it becomes heated, whereas the non-expanding metal rod 23 does not expand. As 30 the tube 10 lengthens in response to heat, the rod 23 moves therewith and the valve 22 is moved away from seat 21', permitting the liquid fuel under pressure to flow from the supply 9 into the generator chamber 15. Since 35 the tube and rod are fixed together, movement of one is experienced in like manner by the other. As the generator tube 10 lengthens in response to heat, the bushing 11^a and valve seat 13 are moved away from valve 17, thereby opening conduit 14 to the burner.

40 It is readily apparent that the foregoing operations do not transpire until the generator is sufficiently heated to vaporize the fuel which may go through into chamber 15.

45 The vaporized fuel may then proceed to the main burner, which is now lighted and the heat thereof continues to serve as the generating flame, in place of the auxiliary flame which may now be manually or automatically shut off. The reverse action takes place in 50 case the auxiliary or main generating flame is inadvertently extinguished for any reason. Under such conditions of the burner, the generator tube 10 contracts as it cools and shortens, thus causing seat 13 to approach and close valve 17, and concurrently valve 22, actuated by the non-expanding rod 23, closes, thereby 55 shutting off both the vapor fuel and liquid fuel supplies.

60 It is apparent that the passageway 31

affords communication from passageway 7 to chamber 15 as aforementioned. If desired the present improvements may be operated in another manner, for example the valve 17 may be retracted from its seat 13, a slight distance at the time of initially heating the generator, or after the generator is heated thereby controlling the outlet of the vapor to the burner. If desired, the modified form in Fig. 3 may be employed with all screw threaded connections of stem 16 omitted.

75 With the present arrangements it is obvious that a novel vapor generator in the form of a heat expansible member is provided in combination with a vapor burner. 80 The number of parts have not only been reduced but greatly simplified. In placing rod 23 alongside the generator, the former is prevented from interfering with the burner flame or utensil thereabove. Furthermore 85 the combination of the heat expansible tube 10 and the needle valve causes the heat to open said valve slightly, thus insuring an exact ratio of the vapor emitted to the tube temperature.

90 It is further notable that the parts as set forth in the modified form are so correlated and coordinated as to establish a ratio therebetween in their functioning. For example, the degree of opening of inlet valve 22 and the degree of opening of outlet valve 17 is proportional to the degree of heat of the burner 5 as well as the degree or extent of the vaporization of the fuel taking place in 95 tube 10. The degree of vaporization is obviously dependent on the heat supplied by burner 5, and the degree of heat supplied is obviously dependent on the vaporization in the tube 10, and the degree of heat supplied also determines the extent that inlet valve 100 105 110 115 120 125 130 22 is opened, thereby determining the amount of liquid fuel supplied to tube 10. It is thus seen that a cycle of dependent functions is established which promotes accurate and proportional control throughout which in the normal functioning of the apparatus is entirely automatic. The adjustable feature of the rod 23 is provided to compensate for wear on the valve seats, or to vary the relation of the valves, if desired.

135 The attendant advantages of the present improvements are apparent. By providing an automatic thermal control on stoves where the liquid fuel is under pressure, the main fuel supply will not open until the stove is sufficiently generated for proper combustion so that the stove can not be flooded with the liquid fuel at the outset and catch fire as is often the case. Should the flame under the generator be extinguished by being blown out by the wind or through other agencies, the valve will automatically close when the temperature of the generator is below the generating or vaporizing degree so that again the stove cannot be flooded with liquid hydro-

carbon and present difficulties and danger when the operator wishes to start it again. In the event that the stove runs out of fuel while in use and the operator forgets to shut off the various valves when starting it after replenishing the fuel supply, the automatically generated thermostatically operated valve will not allow any fuel to pass through the generator until the stove has been regenerated to the proper temperature.

Other advantages and modifications of the present improvements will be apparent to those skilled in the art and may be adopted without departing from the scope and purview of the invention.

I claim:

1. In a device of the character described, the combination with a vapor burner, of a vapor generator comprising a thermally responsive tube communicating therewith and positioned for being heated thereby, a valve controlled fuel supply inlet for said generator, and a non-expansive rod outside of and operatively connected with said generator cooperating therewith for controlling said valve and means controlling communication between said generator and burner in response to thermal conditions of said burner.

2. In a device of the character described, the combination with a vapor burner, of a vapor generator comprising a thermally responsive element, said generator having a liquid fuel supply inlet and a vapor outlet communicably connected with said burner, a valve for said fuel inlet and a valve for said vapor outlet, means operatively connected with said generator for controlling said valves, said generator positioned for being heated by said burner whereby the opening and closing of said valves is proportional to the thermal conditions of said burner.

3. In a device of the character described, the combination with a vapor burner, of a vapor generator comprising a thermally responsive element, said generator having a liquid fuel supply inlet and a vapor outlet communicably connected with said burner, a valve for said fuel inlet and a valve for said vapor outlet, means operatively connected with said generator for controlling said valves, said generator positioned for being heated by said burner whereby the opening and closing of said valves is proportional to the degree of vaporization of the fuel in said generator.

4. In a device of the character described, the combination with a vapor burner, of a vapor generator comprising a thermally responsive element, said generator having a liquid fuel supply inlet and a vapor outlet communicably connected with said burner, a valve for said fuel inlet and a manually operable needle valve for said vapor outlet, means operatively connected with said generator for controlling said valves, said gen-

erator positioned for being heated by said burner whereby the opening and closing of said valves is proportional to the thermal condition of said burner.

5. In a device of the character described, the combination with a vapor burner, of a vapor generator comprising a thermally responsive tubular member communicating therewith and positioned for being heated thereby, a valve controlled fuel supply inlet for said generator, and a substantially non-expansive rod outside of and operatively connected with said generator cooperating therewith for controlling said valve by the relative expansion between said generator and rod.

6. In a device of the character described, the combination with a vapor burner, of a vapor generator comprising a thermally responsive tube communicating therewith and positioned for being heated thereby, a valve controlled fuel supply inlet for said generator and means outside of and operatively connected with said generator for controlling said valve by the relative expansion between said generator and said means.

7. The combination with a vapor burner, of a vapor generator comprising a thermostatic tube communicating therewith and positioned for being heated thereby, a fuel inlet member for said generator, a rigid member outside of said generator and including a valve for controlling said inlet, said rigid member extending along and substantially parallel with said generator and being operatively connected thereto for controlling said inlet by the relative expansion between said generator and rigid member.

8. The combination with a vapor burner, of a vapor generator comprising a thermally responsive tube communicating therewith, said tube having a fuel inlet at one end thereof and a fuel outlet at the other end thereof, a valve controlling said inlet, a rod outside of said generator, connected to and extending from said valve along said generator and being rigidly connected to said generator adjacent the outlet end thereof, said rod and generator being disposed above said burner whereby said valve is controlled by the relative expansion between said generator and rod.

9. In a device of the character described, the combination with a vapor burner, of a vapor generator comprising a tube communicating with said burner and having a fuel supply inlet, said tube being heated by said burner, a valve for controlling said inlet, and a substantially non-expansive member outside of said generator for connecting said valve and generator to actuate said valve upon movement of said generator.

10. In a device of the character described, the combination with a vapor burner, of a vapor generator comprising a tube communi-

cating with said burner and having a fuel supply inlet, said tube being heated by said burner, and a substantially non-expansible member positioned outside of said generator and a valve movable by said non-expansible member for controlling said inlet upon movement of said generator.

5 11. In a device of the character described, the combination with a vapor burner, of a vapor generator comprising a heat expansible tube communicating with said burner and having a fuel supply inlet, valve actuating means outside of said generator for controlling said inlet and connected with said generator for relative movement therewith upon 10 operation of the burner.

10 12. In a liquid fuel stove, a generator comprising a metallic tube, means at one end of said tube forming a passage for conducting liquid fuel into said tube, a valve for controlling the flow of liquid through said passage, and operating means for said valve including a rod having a smaller coefficient of 15 expansion than said tube and extending from said valve along said tube substantially to the other end thereof, means rigidly connecting said rod to said other end of the tube whereby expansion of said tube serves to move said rod to operate said valve.

15 13. In a liquid fuel stove, the combination of a metallic generator tube, means at one end of said tube forming a passage for conducting liquid fuel to said generator, valve means for closing said passage, and valve 20 operating means including a rod formed from metal having a smaller coefficient of expansion than said tube, said rod being positioned along said tube substantially parallel thereto and being adjustably connected to said tube 25 at the other end thereof.

20 Witness our hands this 17th day of October, 1928, county of Milwaukee, State of Wisconsin.
